BAFFLE PLATE FOR PRECOOLER

Tully De Stefani, Chicago, Ill., assignor to Bas-
tian-Blessing Company, Chicago, Ill., a corpo-
ration of Illinois

Application September 26, 1940, Serial No. 358,391

2 Claims. (Cl. 62—89)

This invention relates to heat transfer means and more particularly to the provision of baffle means which are economical in manufacture and highly efficient in use.

It is an object of this invention to provide in cabinets of the refrigerator type, a means for dividing such cabinet into a compartment intended to contain articles for immediate use and a second compartment for containing articles for storage purposes.

Another object of this invention is the provision in cooling cabinets having a compartment for transient articles and a compartment for storing like articles, of a means for dividing the foregoing compartments and for distributing cooling transfer within the cabinet.

A still further object of this invention is the provision in cabinets provided with article storing magazines, of baffle means for providing a precooling chamber and for limiting the rate of heat transfer from articles in the precooling chamber into the articles in the storage magazines.

Other objects and advantages of the present invention will appear more fully in view of the specification and drawings, wherein

Fig. 1 is a fragmentary vertical section through a cabinet embodying the present invention;

Fig. 2 is a horizontal plan section as seen from lines 2—2 in Fig. 1;

Fig. 3 is a fragmentary perspective view of a portion of the cabinet seen in Figs. 1 and 2; and

Fig. 4 is a fragmentary sectional detail view taken along lines 4—4 of Fig. 2, and being at slightly enlarged scale with respect thereto.

This present invention is a continuation in part of my co-pending application Serial No. 198,155, filed March 25, 1938, wherein a more detailed description is devoted to the refrigerating means and article dispensing unit employed therein.

In the present invention there is provided a refrigerator cabinet 10, having cooling elements in the form of coils 11 suspended from an upper wall 12 of the cabinet. The front wall of the cabinet is provided with a hinged closure member in the form of a door 13 whereby to gain access to the interior of the cabinet.

The cabinet 10 is provided with suitable article storing magazines 14, in the present instance in the form of an article supporting drum 15, wherein articles or units, in the present showing such as bottled goods 22, the contents of which are to be kept in a cool and palatable condition, are retained until removed by any suitable

means, either manual or automatic, not shown, but more particularly described in my aforementioned application.

The article storing magazine may be supported in any suitable manner as for instance the manner pointed out in the drawings wherein a shaft 16 is centrally supported in a vertical condition in the cabinet as at 17 on the lower wall 20 of the cabinet and with any suitable flanged bracket as the member 18 for supporting the upper end of the shaft. The magazine support further being provided with a bracket member 19 spaced a substantial distance above the floor 20 of the cabinet and providing an annular flange 21 upon which article carrying dollies are supported. It is to be noted that articles 22 in the magazine 14 are adapted to be rotated with the magazine 14 by any manual control not shown to bring the articles stored in the magazine in a position preparatory to exit from the cabinet.

The article supporting means 14, 15, is disposed in the upper area or portion 23 of the interior of the cabinet, there being sufficient room beneath the supporting bracket 19 for storage of like articles 22' for the purpose of pre-cooling the latter prior to their placement in the upper storing magazine. The space beneath the bracket 19 may therefore be termed a pre-cooling compartment 24.

In the art of refrigerators it is a well-known principal that the temperature variations within the cooling compartments assume a series of strata varying in temperature and rising in degree as they approach the ceiling of the compartment. Such characteristics of necessity would cause the heat of articles such as 22' placed in the pre-cooling compartment to transfer directly to the articles 22 arranged in the higher regions of the compartment 23.

To prevent a sudden transfer of heat from the articles in the lower chamber to those in the higher regions of the upper chamber, applicant provides a baffle means 25 in the form of light metal plates 26 and 26' which act as a deflector member with regards the current of cool air descending from the cooling coils 11.

In the present instance the baffle 25 comprises a pair of plates 26, 26'. Each of these plates has a slotted opening 27 formed at one edge thereof whereby each of the plates may be positioned in its respective half portion of the interior of the cabinet. The members 26, 26' are each provided with elongated slots 28 formed therein extending in a plane parallel with the slot 27. Each plate is mounted on the under side of the brack-

et 19 by means of a headed machine screw 29 (Fig. 4) and in a manner such that each of the plates may be shifted in a direction transversely with respect to the inner confines of the cooling cabinet 10.

As seen in Fig. 2, the baffle plates 26 and 26' overlap each other and are of a width as to provide fixed passages 30 and 31 within the cabinet along the rear and front walls thereof. The baffle further being adjustable with respect to the width of the cabinet so as to provide an additional passage at the side walls of the cabinet or to completely shut off or dispense with a passage at the side walls aforesaid.

The baffle member 25 as heretofore stated acts as a deflector member of the descending air currents and by reason of the fact that the air currents play across the surface of the baffle 25 such baffle would in use become a part of the temperature regulating system in that it would assume a temperature commensurate with the interior temperature of the cabinet. The baffle plate being suspended above the pre-cooling chamber, by reason of its heat transferring properties would provide for the articles 22' in the pre-cooling chamber a means for uniformly transferring the heat from said articles. The heat which rises from the articles 22' would directly contact the bottom surface of the baffle 25 and thereby be dissipated before rising to the upper areas of the dispensing chamber 23. The baffle 25 absorbs the greater quantity of heat which rises from the articles in the pre-cooling chamber and by reason of its being in the path of descending cool air currents will make the heat transfer a gradual process thereby assuring that the cooling coils 11 may sufficiently extract the heat transferred from the articles without danger of a great amount of heat collecting in the upper area of the dispensing compartment 23.

The passages 30 and 31 provided at the front and side walls of the interior of the cabinet permit a descension of a portion of the cooling air currents into the pre-cooling chamber so that the heat transferring action may take place between the articles 22' and the baffle 25. The quantity of articles stored in the pre-cooling chamber usually varies according to the stock on hand, for this reason the baffle member is adjustable on pin and slot mountings 29-28. When the chamber 24 is filled to its maximum capacity the plates 26 and 26' of the baffle member will be extended on the pin and slot mount-

ings 29-28 so that the outer edge 32 of each of these plates will abut the side walls of the cabinet and thereby restrict or limit the rate of heat transfer from the articles 22' to the cooling coil

5 11. The heat transferring action between the articles 22' and the cooling element 11 may be sped up in point of time by contracting the plates 26, 26' whereby to permit a greater amount of cooling air currents to descend into the pre-cooling chamber.

10 While the baffle plate of my present invention is disclosed as employed in a refrigerator cabinet having the characteristics of an article vending device, it is obvious that the objects and advantages of the baffle plate is applicable to all types of refrigerator cabinets for the purpose and economies intended.

15 While I have illustrated and described the preferred form of construction for carrying my invention into effect, this is capable of variation and modification without departing from the spirit of the invention. I, therefore, do not wish to be limited to the precise details of construction set forth but desire to avail myself of such 20 variations and modifications as come within the scope of the appended claims.

25 Having thus described my invention, what I claim as new and desire to protect by Letters Patent is:

30 1. In combination with a refrigerator cabinet having a dispensing chamber with article supporting means disposed therein, and a pre-cooling chamber arranged below said dispensing chamber, of baffle means suspended from said article supporting means, said baffle means comprising corresponding slidable portions whereby communication between said dispensing chamber and said pre-cooling chamber may be varied.

35 2. In combination, a refrigerator cabinet, an article supporting shaft positioned vertically within said cabinet, baffle means supported by the shaft within the refrigerator cabinet and dividing the cabinet into an upper cooling chamber and a lower precooling chamber, said baffle means comprising oppositely arranged semicircular plates, and means for adjustably connecting the plates together, whereby said plates may be adjusted so as to increase or decrease the distance 40 between the periphery of the plates and the adjacent inner walls of the cabinet, substantially as described.

45 50 TULLY DE STEFANI.
